(57) **CLAIM**

The ornamental design for a toy, container, and candy combination, as shown and described.

DESCRIPTION

FIG. 1 is a front right perspective view of a toy, container, and candy combination showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an exploded perspective view thereof, shown in an environment of use;

FIG. 9 is an exploded perspective view thereof, shown in an alternate position; and,

FIG. 10 is a front right perspective view thereof, shown in an alternate position.

The portions of the toy, container, and candy combination shown in broken lines form no part of the claimed design.
